KENNETH EDGAR CLAYTON-KENNEDY, OF NEW YORK, N. Y., ASSIGNOR TO AMERICAN HYDROCARBON COMPANY, INC., A CORPORATION OF DELAWARE.

APPARATUS FOR DISTILLING OIL SHALE.

Application filed May 4, 1926. Serial No. 106,599.

It is well known that large quantities of hydrocarbon oil are contained in shale, and various attempts have been made to obtain this oil on a commercial scale. The present 5 invention is directed more particularly to this problem, but is capable of various other analogous uses.

A general object of the invention is to reduce the expense of obtaining the product, 10 more particularly of obtaining oil from shale. More particular objects of the invention are to provide an apparatus which is simple in construction, inexpensive to manufacture, economical to operate, and which 15 for a given size of apparatus will have a greater production capacity or output than other apparatus heretofore proposed. Further objects of the invention are to secure a more effective application of heat to the material being treated, better agitation of the fragmentary solid material in the apparatus, the more effective exclusion of air from entering the apparatus while the solid material to be treated is being fed thereto and the 20 solid material which has been treated is being discharged therefrom, and a more uniform and reliable feeding to the apparatus of the material to be treated therein. Other 25 objects and advantages of the invention will 30 hereinafter appear.

In carrying out the invention an annular rotating retort is employed mounted to rotate on a longitudinal axis which at least 35 approaches substantially to the horizontal, together with means for maintaining both the inner and outer annular walls of the retort in a substantially uniformly suitably heated condition, means being provided for carrying and distributing the fragmentary 40 solid material being treated completely circumferentially around the annular retort so that it will come into contact with both of the heated annular walls thereof and at the same time will be loosened and thoroughly 45 agitated. In addition to its circumferential movement within the retort, the material being treated continuously travels longitudinally in the rotating retort, being fed in at the one end thereof and the treated material 50 being discharged at the other end thereof, and means are provided by which the entrance to the retort is at all times maintained in a closed condition to exclude air while at the same time the material to be

treated is supplied and fed into the rotating retort. At the other end of the retort the solid material which has been treated and the vapors which have been produced in the retort are received in a separating chamber having a sealing connection to the rotating retort, this chamber having an opening in its bottom and means are provided for constantly maintaining this opening in a closed condition to exclude air and at the same time for discharging or removing the solid treated material from the chamber. The vapors generated in the rotating retort are drawn off from the separating chamber and condensed. A positively acting feed device is provided to force the material to be treated into the retort in desired regulated quantities while the retort is rotating. The invention further includes various features of construction and combinations of parts as will appear from the following description. 75

The apparatus illustrated in the accompanying drawings as one embodiment of the invention and for carrying out the method thereof will now be described and thereafter the invention will be pointed out in 80 claims, reference now being had to the drawings in which:

Fig. 1 is a central vertical longitudinal section of an apparatus embodying the invention;

Fig. 2 is a transverse vertical section of the annular retort on the line 2-2 of Fig. 1;

Fig. 3 is a vertical section on the line 3-3 of Fig. 1, showing the air excluding feed device;

Figs. 4 and 5 are views similar to Figs. 1 and 2 respectively, showing a modified construction.

In the apparatus illustrated in the drawings as an embodiment of the invention, and for carrying out the process or method thereof, an annular axially extended or longitudinally elongated vaporizing space is provided between inner and outer annular walls of which the inner wall 1 is shown as cylindrical and the outer wall 2 is shown as having the form of a truncated cone. These walls form the inner and outer walls of an annular rotating retort and are rotatable upon longitudinal axes which, most desirably, at least substantially approach to the horizontal. In the construction shown in the drawings the inner and outer walls 1 and

2 are shown as arranged concentrically for rotation upon the same axis, which is shown as horizontal. However, according to the broader aspect of the invention, it is not essential that the axes of the annular walls 1 and 2 of the retort shall be either horizontal or coincident, as shown; for example, the axis of the inner wall 2 could be inclined more or less towards the delivery or discharge end of the retort, or the axes of both of these walls 1 and 2 could be more or less thus inclined, also, if desired, these axes, that is to say, the annular walls 1 and 2, may be adjustable in this respect. Also, in the broader aspect of the invention, the outer annular wall of the retort may be cylindrical, similarly to its inner annular wall 1, or may be increased in diameter by steps from its inner to its outer end, or the inner wall 20 of the retort might be of a different contour than that shown for the wall 1. The annular walls 1 and 2 of the annular retort may be rotated together at the same angular speed or they may be rotated independently 25 of or relatively to each other at different angular speeds, either in the same or in different directions of rotation, as will herein-after appear.

According to the invention, means are provided for applying suitable vaporizing heat to both the inner and outer annular walls 1 and 2 of the annular retort substantially throughout their extent, and such means shown as employed in carrying out the invention will now be described. The inner cylindrical wall 1 of the annular retort has secured within its end combined spacing and sealing rings 3 and 4 within which are secured the ends of a cylindrical jacket wall 5 which, together with the end rings 3 and 4, forms a hermetically sealed annular jacket for the inner wall 1 of the annular retort. The closed cylindrical space between the inner retort wall 1 and its jacket wall 5 is shown as filled with a suitable liquid 6 such as a suitable metal in a molten condition. The outer conical wall 2 of the retort carries on its outer side a conical jacket wall 7 which, at the ends of this retort wall, is supported thereon and spaced therefrom by means of sealing rings 8 and 9, thereby to form a hermetically sealed annular jacket which is shown as filled with a suitable liquid 10 such as a suitable metal in a molten condition, which may be the same in kind as the molten metal 6 contained in the jacket for the inner wall 1 of the annular rotary retort. The walls 1 and 2 of the retort and their jackets may be of iron or steel, and the kind of metal to be contained in a molten condition in these jackets may be chosen as to its suitability, for example, according to the amount of heat desired. Such metal may be bismuth, lead, sodium, potassium, or other metal fusible at a relatively low temperature,

and in some cases mercury might be employed. Also in some cases a granular material instead of a fluid may be employed.

Heat, which may be supplied by any suitable means, for maintaining the molten metal in the jackets in a molten and suitably heated condition is applied to the inner jacket wall 5 from within the cylindrical open space enclosed thereby, and also to the outer side of the outer jacket wall 7. In the construction shown in the drawings, burners 11 for gas or liquid fuel are provided within the inner jacket wall 5, a stationary baffle plate 12 being shown above these burners for spreading and distributing the heated products of combustion. Obviously any number of such burners desired may be employed, together with a baffle plate therefor. The burners 11 are supplied with fuel through a pipe 13 which enters through one of the open ends of the jacket wall 5, as hereinafter more particularly described, and is shown as entering the jacket wall 5 at the discharge or delivery end of the retort. As also hereinafter more particularly described, one of the open ends of the jacket wall 5 may have a connection to a chimney so as thereby to create a draft of combustion-supporting air through the jacket as well as to carry away the used products of combustion. The means for applying heat to the outer jacket wall 7 of the annular rotating retort includes a wall forming a stationary hood 14 which covers and encloses the greater portion of the outer jacket wall 7 between the ends of the retort, for confining heated products of combustion which may be supplied at the bottom below the retort by any suitable means, such as burners (not shown) similar to the burners 11. These products of combustion after having served their purpose may escape through an opening 15 in the top of the hood 14 which, if desired, may have a connection to a chimney.

The annular vaporizing space within the retort between its inner and outer walls 1 and 2 is open at both ends and the fragmentary solid material to be treated, such as suitably crushed or pulverized oil bearing shale, is fed into the smaller end of the retort as determined by its conical outer wall 2, and the treated solid material from which the vaporizable matter has been removed is delivered or discharged from the other or larger end of the retort together with the vapors produced or generated in the retort. As the retort rotates the solid fragmentary material which is being treated therein will travel through the retort from the intake or feed end thereof to and out of the discharge end by reason of the downward inclination of the lower portions of the conical or flaring outer retort wall 2, as will be readily understood. As the material being treated travels longitudinally through the

retort it is carried upwardly and distributed circumferentially around the annular retort so as to come into contact with both the inner and outer heated walls 1 and 2 thereof and 5 at the same time is thoroughly agitated, and the means provided for thus distributing and agitating the material will now be described.

The outer flaring or conical wall 2 of the 10 retort has secured thereto within the retort a circumferential series of equidistantly spaced longitudinal inwardly projecting ledges 16 shown as forming flat radial shelves although these ledges could be otherwise shaped so as to carry more material if 15 desired. In the drawings these ledges 16 are shown as angles, which may be angle-irons, one flat web of which forms the ledge and the other of which provides for securing the 20 ledge to the retort wall 2. The inner cylindrical wall 1 of the retort on its periphery within the retort is similarly provided with a similar series of ledges or shelves 17 secured thereto, which are shown as flat and 25 as projecting radially, and which cooperate with the ledges 16 carried by the outer wall 2 of the annular retort. Also, if desired, the flat ledges or shelves 17 may be of a different shape so as thereby to receive and 30 carry a larger quantity of material. The ledges or shelves 16 and 17 of the outer and inner series thereof are shown as of the same width in any transverse plane, these ledges gradually increasing in width from 35 the feed or intake end of the annular retort to the delivery or discharge end thereof. A safe clearance is provided between the adjacent edges of the outer and inner ledges or shelves 16 and 17, as shown, thereby providing, 40 when desired, for the differential rotation of the inner and outer walls 1 and 2 of the annular retort or for their rotation in opposite directions, as hereinbefore mentioned, as well as providing for the free and effective transfer of the fragmentary solid 45 material back and forth from each to the other of the two series of shelves 16 and 17. Of course the annular retort space is never 50 completely filled with the fragmentary solid material but sufficient free or open space is left therein for the free transfer of such material back and forth in a loose condition from the outer wall 2 to the inner wall 1 and then back again from the inner wall 1 to 55 the outer wall 2 of the annular retort, the extent to which the retort is filled being to some extent dependent upon the nature of the material being treated.

With the inner and outer walls 1 and 2 60 of the annular retort rotating in the same direction the material carried by the shelves 16 in the pockets formed thereby will gradually or progressively drop therefrom away from the outer wall 2 upon the shelves 17 65 and into the pockets formed thereby with

the inner wall 1 so that at the ascending sides of the walls 1 and 2 the material is gradually or progressively transferred from the pockets of the outer wall 2 to the pockets of the inner wall 1, dropping loosely and 70 freely from the outer wall 2 and its shelves 16 to the inner wall 1 and its shelves 17. Such material is carried in a constantly shifting condition over the top of the cylindrical inner wall 1 in contact 75 therewith between the shelves 17 thereof. At the descending sides of the radially spaced walls 1 and 2 of the annular retort such material gradually and progressively 80 freely drops in a loose condition from the shelves 17 away from the inner cylindrical wall 1 upon the shelves 16 and outer conical wall 2 by which such material is carried in a constantly shifting condition from one side to the other across the bottom of the 85 annular retort, again to repeat its circumferential travel in the annular retort, during which it is to be noted such material is thoroughly agitated and effectively subjected to the vaporizing heat of the walls 1 90 and 2 and of their pocket-forming shelves 17 and 16 and at the same time progressively travels longitudinally through the annular retort from end to end thereof. As the 95 retort rotates the material cascades from shelf to shelf, particularly back and forth between the two series of shelves.

When the inner and outer walls 1 and 2 of the annular retort are rotated, as herein-after more particularly described, each of 100 these walls of course carries with it its own series of cascaders or shelves 17 and 16, respectively, independently of the other series. These retort walls 1 and 2 may be rotated together in the same direction at 105 the same angular speed, and in such case may be directly coupled or connected together if desired. However, in treating materials which have a tendency to agglomerate into cakes or masses, for example, resinous materials such as some bituminous shales, these inner and outer walls 1 and 2 of the annular retort should be rotated, at times at least, at different rates 110 of speed and occasionally or from time to time it may be desirable to rotate these walls in opposite directions. By such differential rotation or by rotation in opposite directions the formation of agglomerations 115 will be more effectively prevented and also any agglomerated masses or cakes which do form will be caught between the adjacent edges of the two series of ledges or shelves 16 and 17 and thereby broken up. For example, in operating in this manner the speed 120 of the outer wall 2 of the annular retort may remain constant while the speed of the inner wall 1 may be changed or reversed.

The outer jacketed conical or flaring wall 125 2 of the annular retort is shown as rotat-

ably supported adjacent its ends on rollers 18 which run on its jacket wall 7 and which are journaled on suitable base supports (not shown). The inner cylindrical wall 1 of the annular retort together with its jacket may be rotatably supported by the outer wall 2 or it may be independently supported or both of such supporting means may be provided as is shown in the drawings. In the illustrated construction, flanged spacing and bearing rings 19 and 20 are shown as interposed respectively between the inner and outer walls 1 and 2 of the annular retort at the intake or feed end thereof and at the delivery or discharge end thereof, the bearing ring 19 at the feed end of the retort being provided in its web throughout the latter with large closely adjacent openings 19^a for the entrance into the retort of material to be treated, while the bearing ring 20 is provided with a similar circumferential series of large closely adjacent openings 20^a for the discharge of the treated solid material from the retort as well as for the exit of the vapors generated in the retort. These openings 19^a and 20^a may be sufficiently large and closely spaced as to leave between them only narrow ribs or spokes so that the traveling movement 30 of the fragmentary solid material into and out of the annular retort is not impeded. For holding them in place these bearing rings 19 and 20 are secured to one of the walls, for example to the outer wall 2, and thus form supporting bearings for the inner cylindrical wall 1.

Outwardly from the discharge end of the rotary retort the end of its inner jacketed wall 1, which is shown as projecting beyond the outer jacketed wall 2, is further supported by means of a bearing 21, supported as hereinafter described, in which is journaled and through which extends a tubular extension 22 of the inner jacketed wall 1 and shown as having its inner end secured within the end of the jacket wall 5. It may be here noted that the hereinbefore mentioned fuel supply pipe 13 is shown as entering the cylindrical jacket wall 5 through the tubular extension 22. In view of the bearing 21 it is evident that the bearing ring 20 could be omitted if desired. Likewise the bearing ring 19 at the feed end of the annular retort could be omitted, and in such case this end 55 of the jacketed wall 1 could be provided with bearing means similar to the bearing 21 and tubular wall extension 22 at the other end of this wall 1 of the retort.

The means provided in carrying out the invention for feeding the fragmentary solid material such as pulverized oil bearing shale to the admission or intake end of the annular retort while the latter is rotating and at the same time substantially excluding air from entering the retort will now be de-

scribed. Obviously if air in any substantial quantities were permitted to enter the retort during its operation not only would the generated vapors be diluted thereby but in all probability a dangerously explosive mixture 70 would be formed with the combustible oil vapors. In the construction shown, the entire feed end of the annular rotary retort is suitably beveled as shown so that the beveled surfaces thereof, particularly of the beveled 75 jacket-sealing spacing rings 3 and 8, may have a sealing fit against the conical sealing surface of a conical end wall 23, while permitting the retort to rotate in contact with the conical stationary end plate 23, thereby 80 to prevent the entrance into the retort of air from the atmosphere and similarly to prevent the entrance into the retort of air and products of combustion present within the inner jacket wall 5. The end wall 23 extends 85 centrally inwardly and is provided somewhat above its center with an open outwardly projecting tubular portion 24 which communicates with the interior of the jacket wall 5 and the outer end of which may be connected to a chimney for creating a suitable 90 combustion-supporting draught of air through the jacket wall 5 as well as for carrying off the products of combustion 95 after the extraction therefrom of their available heat. Also the end wall 23, which may conveniently be a casting, is provided with a base plate 25 by means of which it may be suitably supported.

In view of the fact that the entire feed 100 end of the annular retort is open completely around its circumference through the holes or openings 19^a the rotation of the annular retort will not in any manner prevent or interfere with the feeding of material thereto while the retort rotates. Also it is obvious and is to be understood that if desired such material may be fed to the rotating retort throughout as large a continuous or discontinuous circumferential space or area 110 or extent as may be found desirable. In the construction shown, the material to be treated is fed to the annular retort as it rotates into whatever portion thereof may be at the bottom or lowermost at the time. In such 115 construction the conical end wall 23 adjacent its lower edge is provided with an outwardly projecting tubular casing 26 having therein a horizontal longitudinal passageway or bore 27 the inner end of which opens through 120 the conical wall 23 directly into the retort between its inner and outer annular walls 1 and 2 as shown in Fig. 1. On its upper side substantially adjacent to the wall 23 this tubular casing 26 is provided with an 125 upwardly projecting and outwardly inclined tubular boss 28 which opens into the bore 27 of the casing 26. The tubular casing 26 projects outwardly some distance beyond the tubular boss 28 for a purpose which will 130

presently appear. The boss 28 has connected thereto the lower end of a downwardly extending and somewhat inwardly inclined imperforate tube 29 forming an air tight feed or supply chute of which the boss 28 forms a continuation into the bore 27 of the casing 26 so that the fragmentary solid material which is to be fed to the retort may descend by gravity through this chute into the bore 27, from which such material is positively fed into the retort by means presently to be described.

Supported by the upper end of the chute 29 and further supported on an outer flange 15 of the end wall 23 is a cylindrical casing 30, the axis of which is horizontal. At its lower side or bottom, through an opening 31 in its cylindrical wall, the casing 30 communicates with or opens into the upper end of the chute 29 which at this point extends vertically. At its upper side or top the cylindrical wall of the casing 30 is provided with a short tubular inlet neck 32. Mounted on the neck 32 and opening into it is a supply hopper 33 for containing a considerable quantity of the fragmentary solid material to be treated which may descend by gravity through the neck 32 into the cylindrical casing 30. Within the cylindrical casing 30 and fitting closely therein both at its ends and peripherally, is a rotatable feed cylinder or drum 34, shown as of greater diameter than length, which at all times closes and seals the casing 30 against the passage of air through this casing into the upper end of the chute 29. In its periphery the cylinder or drum 34 is provided with a suitable recess to form therein a pocket which may be relatively large as compared with the dimensions of the drum 34. In the construction shown in the drawings, there is provided within this drum 34 a pocket 35 of a size so large that it leaves only end walls and a peripheral wall which latter wall is incomplete or discontinuous to provide a large opening or mouth 36 for the pocket 35, as appears most clearly in Fig. 3. The mouth 36 of the pocket 35, however, is made sufficiently small that the opening in the top of the casing 30 through the neck 32 as well as the opening 31 in the bottom of the casing 30 will at all times be closed and sealed by the peripheral wall of the drum 34. At its end adjacent the retort end wall 23 the drum 34 is provided with a stub shaft 37 journaled in an outwardly closed bearing 38 on the casing 30 for rotatably supporting the drum 34 at this end. At its other end the drum 34 is fixed to a supporting and operating shaft 39 which is journaled in and projects outwardly beyond a bearing 40 on the casing 30. For rotating the drum 34 its operating shaft 39 has fixed thereon a pulley 41 over which runs a belt 42, in the construction shown. This operating shaft 39, by means of the belt 42, may be driven by any convenient source of power, such as from a line shaft or by a suitable motor, for example, an electric motor.

As the drum or cylinder 34 rotates, when 70 its mouth 36 comes upward so to register or communicate with the opening through the tubular neck 32, the fragmentary solid material will descend by gravity from the hopper 33 through the neck 32 and mouth 75 36 and will fill the pocket 35 in the sealing drum 34, then when the mouth 36 comes into registration or communication with the opening 31 in the bottom of the casing 30, by reason of the continued rotation of the 80 drum 34, such material will drop out of the pocket 35 through the mouth 36 and opening 31 into the upper end of the supply chute 29. During this operation no or substantially no air can enter the chute 29 85 from the atmosphere excepting merely the small quantity thereof contained in the interstices between the small pieces of the fragmentary solid material. Excepting for the constant seal formed by the rotating drum 34 in the casing 30, air from the outside would have a tendency to enter the retort, particularly by reason of the partial vacuum maintained within the retort, as will presently appear. The material contained in the hopper 33 assists in maintaining a seal against the entrance of air to the retort, and by keeping the feed chute 29 filled or nearly so with the material to be treated, this material in the chute will also 90 similarly assist in forming a more effective seal against the entrance of air to the retort.

Gravity is not relied upon to feed the material to be treated from the chute 29 into the retort, but in carrying out the invention 105 a positively acting feed device or stoking device is provided which assures the unfailing feeding of the material to be treated to the retort in desired regulated or measured quantities without the possibility of irregular feeding or the clogging of such material, and such device will now be described. The material to be treated descends by gravity from the chute 29 into the bore or passage 27 of the tubular casing 110 26. The bore 27 extends outwardly entirely through the casing 26 which projects beyond its tubular boss 28 which, as above noted, forms a continuation of the chute 29. The bore 27 snugly but slidably contains a reciprocating plunger 43 which at its outer end extends beyond the casing 26. In addition to the snug sliding fit of the plunger or piston 43 in the bore 27 of its casing or cylinder 26 this casing is shown as further sealed against the entrance of air into the retort by means of a packing flange including a usual sealing ring 44 for compressing a gasket against the piston or plunger.

As the plunger 43 is retracted its inner 120 125 130

end clears the chute opening provided through the boss 28 so that the passage 27 at the front of the plunger becomes filled with material from the chute 29. As the 5 plunger 43 moves forward or inward it pushes before it the material in the passage 27 and forces such material through the end wall 23 of the rotating annular retort into the latter. It is desirable that the plunger 10 43 shall be reciprocated in harmony with the rotation of the drum 34 so that the plunger 43 may feed at its full capacity and leave some material in the supply chute 29 and also, although of small consequence, to permit 15 the supply drum 34 to deliver at its full capacity into the supply chute 29. As shown in the drawings, the feed plunger 43 is reciprocated by means of a pitman or connecting rod 45, a crank 46, bevel gears 20 47, a shaft 48, a pulley 49, a belt 50, and a pulley 51 fixed on the shaft 39 which rotates the material-supplying sealing drum 34, so that the feed plunger 43 will be reciprocated at a rate commensurate with the 25 rotation of the drum 34, thereby to keep the supply chute 29 substantially filled with material.

At the delivery or discharge end the annular rotary retort opens into a stationary 30 receiving and separating chamber 52 which receives from the retort the vapors which have been produced therein and also the solid material from which the vaporizable matter has been extracted. This chamber is shown 35 as having vertical parallel side walls and as elongated somewhat in a vertical direction. The delivery or discharge end of the annular rotary retort enters the chamber 52 through one of these side walls, the outer 40 jacket wall 7 having a sealing relation with this wall for substantially excluding air from the chamber 52 and the retort, and this seal may include a gasket and a sealing ring 53 therefor as shown. To provide for longitudinal 45 expansion and contraction of the jacketed retort wall 2, its jacket wall 7 is made cylindrical at this point, as shown. The bearing 21 for the tubular extension 22 of the inner jacketed wall 1 of the annular 50 retort is provided on the other above mentioned vertical wall of the chamber 52 and forms a seal against the entrance of air into the chamber 52, this seal being shown as made more secure by means of a packing 55 gland flange having a ring 54 carried by the bearing 21. If desired, the bearing 21 may be mounted for vertical, or other, adjustment on the wall of the chamber 52.

The receiving and separating chamber 52 tapers downwardly at its bottom and is there provided with an outlet opening 55 for the solid fragmentary material. At its outlet opening 55 the chamber 52 is connected to an air-excluding discharge device which 60 may be and is shown as similar in construc-

tion to the air-excluding feed device connected between the hopper 33 and the chute 29, as hereinbefore described. This discharge device has a cylindrical casing 56 connected to the bottom of the chamber 52 and into the top of the periphery of which the chamber outlet 55 opens, while the bottom of the peripheral part of this casing is shown as opening into the upper end of a discharge pipe 57 connected thereto. The 70 casing 56 rotatably but snugly contains a cylindrical discharge drum 58 having therein a discharge pocket 59 which opens at one side of the periphery of the drum 58 so as to communicate alternately with the outlet 75 opening 55 of the chamber 52 and with the discharge pipe 57. The drum 58 has a short shaft 60 journaled in an outwardly closed bearing on the casing 56 and at its other end is fixed upon the inner end of a driving 80 shaft 61 journaled in and projecting outwardly beyond a bearing on the casing 56. The driving shaft 61 has fixed thereon a pulley 62 for a belt 63 by means of which the discharge drum 58 may be rotated by any 85 convenient source of power, for example, an electric motor or from a line shaft. The drum 58 at all times substantially seals the casing 56 against the entrance of air through the discharge pipe 57 and this casing into 90 the chamber 52 through its outlet opening 55, however, as the drum 58 rotates it will discharge the fragmentary solid material from the bottom of the chamber 52 through its outlet opening 55 and into the discharge 95 pipe 57. The discharge drum 58 should be rotated at a rate in harmony with the rate of rotation of the feed supply drum 34 so that it will discharge the treated solid material at a rate commensurate with the rate 100 at which the fresh or untreated material is supplied by the drum 34. Obviously it is desirable that the pocket 59 in the discharge drum 58 should be substantially filled, while, on the other hand, it is obvious that solid 105 material cannot be permitted to accumulate progressively in the bottom of the chamber 52.

While the solid fragmentary material from which the vaporizable matter has been 110 driven off falls from the open end of the annular rotating retort, dropping to the bottom of the chamber 52, from which it is constantly removed, as above described, the vapors generated within such retort between 115 its heated annularly spaced walls 1 and 2 issue from the same open end of the annular rotating retort and fill the receiving chamber 120 52. The vapors may be conducted away from or drawn off from the receiving or separating chamber 52 by any suitable means. In the construction shown in the drawings an eduction pipe 64 connected to the top of the chamber 52 leads to a rotary exhaust pump 65 which may be of the centrifugal 125 130

type as indicated in Fig. 1. The pump shaft 66 has fixed thereon a pulley 67 to be driven by a belt 68 from any suitable source of power, such as a line shaft or a motor, which 5 may be an electric motor. From the delivery side of the exhaust pump 65 a pipe 69 leads to a condensing apparatus, shown as a coil or worm 70, in which the vapors are condensed and from which they are delivered 10 as a liquid or distillate.

The rotary annular retort comprising the inner and outer jacketed walls 1 and 2 and the several parts carried thereby may be rotated by any suitable means. As herein- 15 before described, according to the particular nature of the material being treated, these walls may be rotated together in the same direction at the same angular speed, or they may be rotated at different speeds in the 20 same direction, or they may be rotated in opposite directions. In the construction shown in the drawings, the outer jacketed ledge-carrying wall 2 may be rotated by means of a sprocket ring 71 fixed upon its 25 jacket wall 7 near its end adjacent to the conical sealing wall 23 at the feed or intake end of the annular retort. By means of a usual sprocket chain the sprocket ring or wheel 71 may be driven from any convenient 30 source of power, such as a line shaft or a suitable motor, such as an electric motor. The inner jacketed wall 1 of the annular rotary retort may be rotated by means of a sprocket ring or wheel 72 fixed on the outer 35 projecting end of its tubular extension 22. This sprocket wheel 72 by means of a usual sprocket chain may be driven from any suitable source of power, such as a line shaft or a suitable motor, such as an electric motor. 40 When the inner and outer walls 1 and 2 of the annular rotary retort are to be rotated together at the same speed, then, if desired, one of the above described driving means may be dispensed with and both of such 45 walls then driven by means of one of the sprocket rings, for example, by means of the larger sprocket ring 71 on the jacket wall 7 of the outer wall 2 of the annular rotary retort. Obviously, all parts of the apparatus 50 may be driven from a single source of power, or they may be driven from, more or less, independent or separate sources of power, as desired.

The operation of the apparatus illustrated 55 as an embodiment of the invention has already been described to a considerable extent so that now there only needs to be added a brief résumé together with a few additional explanations. The fragmentary solid 60 material from which the vaporizable matter is to be extracted is supplied and positively fed into the intake end of the annular rotating retort uniformly in constant quantities while air is effectively excluded or prevented 65 from entering the retort at this end. The

molten metal 6 and 10 is maintained in a molten and desired uniformly heated condition by means of the heat in the combustion chamber formed by the inner jacket wall 5 and by that in the combustion chamber 14 70 surrounding the outer jacket wall 7. This molten metal maintains the inner and outer walls 1 and 2 of the annular rotary retort in a uniformly suitably heated condition throughout. The heat to which the fragmentary solid material within the retort is subjected is just sufficient to vaporize effectively and efficiently the vaporizable matter without the temperature being sufficiently high to cause the production of fixed or 80 permanent gases. As the annular retort rotates the fragmentary solid material therein is distributed circumferentially around it, at the same time being thoroughly agitated and broken up, while it travels 85 longitudinally through the retort. Because of the annular shape of the retort and the distribution of the material circumferentially around it between its spaced inner and outer walls 1 and 2, this retort is enabled 90 to contain a greater quantity of the solid fragmentary material than if it were otherwise shaped. Also by reason of the fact that the annular construction provides a larger heating surface and that the material is 95 brought into contact with substantially all of this surface, the material while passing through the retort is more effectively subjected to vaporizing heat. In fact, with an annular retort such as is shown in the drawings more than 80% of its available heating surface may be utilized whereas in retorts such as heretofore employed only about 20% or less of their relatively smaller heating surface can be utilized. Because of the longitudinal progressive increase in cross sectional area or size of the annular retort chamber or space between its inner and outer walls 1 and 2 away from the intake or feed 100 end of the annular retort towards its delivery or discharge end, the vaporizing action is facilitated and improved results are secured. Also it may be noted that air is effectively excluded from entering the discharge end of the retort and the receiving 105 or separating chamber 52, while the fragmentary solid material from which the vaporizable matter has been removed is constantly discharged from the latter and the vapors drawn off therefrom and condensed. 110

For some materials, such as coal, which when heated become sticky and would have more or less of a tendency to adhere to and accumulate on the walls of the annular rotary retort, particularly the outer wall 125 thereof, the modified construction shown in Figs. 4 and 5 may be employed. In this construction the distributing and agitating plates 73, shown as six in number, carried by the conically flaring outer jacketed wall 130

74 of the annular retort are of the same width throughout their length, so that their free edges are parallel to this wall. The free edges of the cooperating tapering distributing and agitating plates 75, also six in number, carried by the inner annular jacketed wall 76, which is shown as cylindrical, are also parallel longitudinally of the retort with the outer flaring wall 74 and 5 normally rotatively clear the adjacent free edges of the plates 73. The inner cylindrical wall 76 is mounted to provide for longitudinal sliding movement. By sliding the inner cylindrical wall 76 longitudinally 10 within the outer conical wall 74 towards the smaller end of the latter, that is, towards the feed end of the apparatus, the free outer edges of the plates 75, which are parallel to the outer conical wall 74, may be brought 15 into contact with the outer conical wall 74, then by partially rotating one of the walls of the retort relatively to the other, any sticky material adhering to the outer wall 74 will be removed by the scraping action of 20 the outer free edges of the plates 75 carried by the inner cylindrical wall 76. 25

In the construction shown, at the feed or intake end of the apparatus, the end of the inner cylindrical wall 76 is shown as closed 30 by means of a circular plate or head 77 secured thereto, and to which is secured the inner end of an operating rod 78 which is guided to slide through a bearing 79 on the stationary end wall 80, the head 77 being 35 rotatably mounted on the inner end of the operating rod 78 and held in place thereon by means of collars on the rod as shown. A connecting rod 81 connects the outer end of the slidable operating rod 78 with a crank 40 82 carried by a transverse shaft 83 journaled in a supporting bracket 84 and having fixed thereon a pulley 85 for a drive belt 86. The crank 82 should be of sufficient length to bring the free edges of the plates 75 into 45 contact with the inner surface of the conical outer wall 74 between its plates 73 and in the construction shown, this crank 82 is made of the correct length to assure that this result shall take place, and at the same time 50 to enable the crank shaft 83 together with the crank 82 to make a complete rotation.

The end wall 80 is provided with an inner cylindrical extension wall 87, which supports and guides within it as well as forms a seal 55 for the adjacent end of the inner cylindrical jacketed wall 76 of the retort. This cylindrical guide wall 87, together with the adjacent end portion of the conically flaring outer wall 74, which is shown as cylindrical at this point, confines and forms a guide 60 for the fragmentary solid material as the latter is fed into the annular rotating retort, and for more effectively performing this latter function this cylindrical wall 87 may be 65 provided longitudinally thereof on its lower

side with a pair of rib walls one of which is shown at 88, which may flare apart in an inward direction for thereby spreading the material fed to the annular retort over a larger arcuate portion thereof, as will be 70 readily understood. The end wall 80 is shown as provided with openings, to prevent the trapping of air between this wall and the head 77.

The distributing and agitating plates 73 75 carried by the outer conically flaring wall 74 terminate adjacent the inner end of the cylindrical guide wall 87, while the cooperating distributing, agitating and scraping plates 75 carried by the inner cylindrical 80 wall 76 terminate at some distance back of or inward from the end of the guide wall 87, thereby to provide for the longitudinal sliding movement of this inner wall 76 into the 85 guide wall 87.

At the delivery or discharge end of the annular rotary retort the combined distributing, agitating and scraping plates 75 carried by the inner cylindrical wall 76 extend, together with this wall, beyond the larger 90 end of the conically flaring outer wall 74 sufficiently so that when the inner wall 76 carrying with it the plates 75 is slid forward toward the feed or intake end of the retort the ends of these plates 75 at the discharge 95 end of the retort will be brought substantially flush with this end of the conical outer wall 74, thereby enabling the entire inner surface of the latter to be cleaned throughout its length by the plates 75. 100

At the discharge end of the annular rotary retort, the tubular extension wall 89, which rotatably as well as slidably supports this end of the inner jacketed wall 76, is extended and projects outwardly beyond its 105 bearing 90 sufficiently to provide for such longitudinal sliding movement through this bearing. The driving sprocket 91 is shown as splined to this tubular extension wall 89, and as held in place against longitudinal 110 sliding movement therewith by means of a bracket or clip 92 secured to the bearing 90 and which at its free end engages, as shown, in an annular groove in the hub of the sprocket 91 by which the inner annular wall 115 76 of the retort is rotated through the tubular extension 89 and its splined connection to the sprocket 91. Combustion supporting air may enter through the lower portion of the outer end of the tubular extension 89 120 and the used products of combustion may escape through the upper portion thereof, although obviously if desired other means could be provided for creating a suitable draught of air and for carrying away the 125 products of combustion.

At any time desired during the operation of the apparatus the crank shaft 83 may be rotated to bring its crank 82 into an opposite position from that shown in Fig. 4, 130

thereby to bring the free edges of the tapering plates 75 carried by the inner sliding wall 76 into rotatively scraping relation with the conical outer wall 74 for cleaning off or removing therefrom any carbonaceous or other material which has accumulated thereon, this being done while the inner and outer walls 76 and 74 of the annular retort are rotated at different speeds, or while one of these walls is held stationary, if so desired, or while these walls are rotating in opposite directions, this being immaterial so far as the scraping operation is concerned. This cleaning of the conical outer wall 74 of the annular retort may take place occasionally under manual control or it may be automatically performed, the crank shaft 83 then being rotated intermittently in timed relation with the differential rotative movements of the inner and outer walls 74 and 76 of the retort. As a measure of safety a slip drive may be provided for one of the walls of the retort if desired. Should it be found desirable to provide for cleaning the inner annular wall of the annular retort this may be accomplished by making this wall also of conical shape similar to the outer wall 74 and parallel therewith, the combined agitating, distributing and cleaning plates on the inner wall then being of the same width throughout their length and also being of the same width as the cooperating plates on the outer wall, so that thereby the plates on the outer wall will be effective to clean the inner wall while plates on the latter wall are cleaning the outer wall. With this latter arrangement briquetting of material may be accomplished between the two sets of plates of the respective walls if desired.

In other respects than above described or shown in Figs. 4 and 5 of the drawings, the construction and operation of this apparatus may be substantially the same as that hereinbefore described with reference to Figs. 1, 2 and 3.

It is obvious that various modifications in construction may be made in the apparatus shown in the drawings as embodiments of the invention, and above particularly described, within the principle and scope of the invention as defined in the appended claims.

I claim:

1. An apparatus for extracting vaporizable matter from fragmentary solid material comprising an annular retort having its inner and outer walls mounted to provide for independent rotation of said walls on longitudinal axes which at least approach substantially to the horizontal, means for rotating one of the annular walls of the retort, means for concomitantly rotating the other annular wall of the retort, means exterior to the retort for maintaining its inner annular wall in a suitably heated condition,

means exterior to the retort for maintaining its outer annular wall in a suitably heated condition, means for feeding the material to be treated into the rotating retort at one end thereof and at the same time substantially excluding the entrance of air into the retort, means for receiving solid treated material delivered from the other end of the retort and at the same time substantially excluding air from the retort, a circumferential series of ledges carried by the outer annular wall of the retort at its inner side for first lifting and then dropping the material being treated as it travels longitudinally through the retort, a similar series of ledges within the retort carried by the inner annular wall thereof for receiving upon said inner wall the material dropped from said outer wall and again returning such material thereto, and means for conducting away and conserving the vapors generated in the retort.

2. An apparatus for extracting vaporizable matter from fragmentary solid material comprising an annular retort having its inner and outer walls mounted to provide for independent rotation of said walls on longitudinal axes which at least approach substantially to the horizontal, means for rotating one of the annular walls of the retort, means for concomitantly rotating the other annular wall of the retort, a closed annular jacket carried by and substantially covering the outer annular wall of the retort containing molten metal, a similar closed annular jacket carried by and substantially covering the inner annular wall of the retort containing molten metal, means for applying heat to the inner annular jacket from within in the space enclosed thereby to maintain the said metal therein in a suitably heated molten condition, means for applying heat to the outside of the outer annular jacket for maintaining the said metal therein in a suitably heated molten condition, means for feeding the material to be treated into the rotating retort at one end thereof and at the same time substantially excluding the entrance of air into the retort, means for receiving and disposing of discharged solid treated material at the other end of the retort and at the same time substantially excluding air from the retort, a circumferential series of ledges carried by the outer annular wall of the retort at its inner side for first lifting and then dropping the material being treated as it travels longitudinally through the retort, a similar series of ledges within the retort carried by the inner annular wall thereof for receiving upon said inner wall the material dropped from said outer wall and again returning such material thereto, and means for conducting away and conserving the vapors generated in the retort.

3. An apparatus for extracting vaporizable matter from fragmentary solid material comprising an annular retort rotatable on a longitudinal axis which at least substantially approaches to the horizontal, the outer annular wall of the retort having substantially the form of a truncated cone, means for rotating the retort, means for applying suitable heat to the outer side of the truncated wall of the rotating retort substantially throughout its extent, means for applying suitable heat to the inner annular wall of the rotating retort within the space enclosed thereby substantially throughout its extent, 10 means for substantially excluding air from the rotating retort and at the same time feeding the solid material to be treated into the retort at the exteriorly smaller end thereof as defined by its truncated outer wall, means for delivering from the other end of the rotating retort the treated solid material which has traveled through the retort and at the same time excluding air from the retort, and means for 15 drawing off from the rotating retort the vapors generated therein.
4. An apparatus for extracting vaporizable matter from fragmentary solid material comprising an annular retort rotatable on a longitudinal axis which at least substantially approaches to the horizontal and having a cylindrical inner wall and a conically flaring outer wall, means for rotating the retort, means for applying suitable heat to the outer side of the conical wall of the retort substantially throughout its extent, means for applying suitable heat to the inner cylindrical wall of the retort within the space enclosed thereby substantially throughout its extent, means for substantially excluding air from the rotating retort and at the same time feeding the solid material to be treated into the retort at the exteriorly smaller end thereof as defined by its conical outer wall, means for discharging from the outer end of the rotating retort the treated solid material which has traveled through the retort and at the same time substantially excluding air from the retort, means for 20 drawing off from the rotating retort the vapors generated therein, and means for agitating the material being treated and distributing it circumferentially around the annular retort comprising ledges within the retort carried by and projecting from the periphery of its inner annular wall, and other ledges carried by and projecting inwardly from the outer annular wall of the retort.
5. An apparatus for extracting vaporizable matter from fragmentary solid material comprising an annular retort having its inner and outer annular walls mounted to provide for independent rotation of said walls on longitudinal axes which at least approach substantially to the horizontal and having its outer annular wall in the shape of a truncated cone, means for rotating the said inner and outer annular walls of the retort, a closed annular jacket carried by and substantially covering said outer annular wall and containing molten metal, a similar closed annular jacket carried by and substantially covering the said inner annular wall within the central space enclosed thereby and containing molten metal, means for applying suitable heat to the exposed walls of said jackets to maintain the molten metal therein in a suitably heated molten condition, means for feeding the material to be treated into the rotating retort at the smaller end thereof as determined by its conical outer wall and at the same time substantially excluding air from the retort, means for delivering the solid treated material from the other end of the retort when the said material has traveled through the retort and at the same time substantially excluding air from the retort, means for drawing off from the retort the vapors generated therein, and means for agitating the material being treated in the retort and for distributing it circumferentially therein comprising inwardly projecting ledges carried by the outer truncated wall of the retort, and other ledges carried by the inner annular wall of the retort and projecting towards its outer truncated wall.
6. An apparatus for extracting vaporizable matter from fragmentary solid material comprising an annular retort having an inner cylindrical wall and an outer conical wall mounted to provide for independent rotation of said walls on longitudinal axes which at least approach substantially to the horizontal, means for rotating said walls, a closed annular jacket carried by and substantially covering the conical wall and containing molten metal, a similar closed annular jacket carried by and substantially covering the cylindrical wall within the space enclosed thereby and containing molten metal, means for applying suitable heat to the exposed walls of said jackets to maintain the molten metal therein in a suitably heated molten condition, means for feeding the solid material to be treated into the smaller end of the annular retort as determined by its conical wall and at the same time substantially excluding air from the retort, a separating chamber with which the other end of the retort communicates for the chamber to receive therefrom the solid treated material and the vapors generated in the retort, means for drawing off the vapors from said chamber, and means for agitating the solid material being treated in the retort and for distributing it circumferentially therein comprising ledges carried by and projecting inwardly from the conical

wall, and other ledges carried by the cylindrical wall of the retort and projecting towards its conical wall.

7. An apparatus for extracting vaporizable matter from fragmentary solid material comprising an annular retort having its inner and outer annular walls mounted to provide for independent rotation of said walls on longitudinal axes which at least 10 substantially approach to the horizontal and having one of its annular walls of conical shape, a longitudinally extending plate carried by and projecting from the other said annular wall of the retort and having its 15 free edge extending in parallel relation to said conical annular wall and normally spaced therefrom, means for rotating the said inner and outer annular walls of the retort, means for maintaining the inner and 20 outer annular walls of the retort in a suitably heated condition, means for causing said material to enter and travel progressively longitudinally through and out of the annular rotating retort, means for conducting 25 away from the annular rotating retort the vapors generated therein, and means for sliding one of said annular walls of the retort longitudinally relatively to the other to cause the free edge of said plate to approach 30 said conical wall while one of said walls rotates relatively to the other so as thereby to cause said plate to remove from said conical wall material adhering thereto.
8. An apparatus for extracting vaporizable matter from fragmentary solid material comprising an annular retort having its inner and outer annular walls mounted to provide for independent rotation of said walls on longitudinal axes which at least 35 approach substantially to the horizontal and having one of the annular walls of conical shape, means for rotating the said inner and outer annular walls of the retort, means for maintaining the inner and outer annular 40 walls of the retort in a suitably heated condition, means for causing said material to enter at one end and travel longitudinally through the annular retort and out at the other end thereof, circumferentially equi- 45 distant plates within the annular retort extending longitudinally thereof carried by and projecting from said conical wall thereof, other circumferentially equidistant longitudinally extending plates within the annular retort carried by and projecting from 50 its other said annular wall and having their free edges parallel with said conical annular wall and normally rotatively clearing the free edges of the said plates on the latter wall, means for conducting away from the rotating retort the vapors generated therein, and means for moving one of said annular walls of the retort longitudinally relatively to the other in the direction and to an extent

to bring into contact with said conical walls 65 between its said plates the free edges of the said plates carried by said other annular wall of the retort so that upon relative movement of said annular walls the said latter plates will scrape from said conical wall 70 material which may have accumulated thereon.

9. An apparatus for extracting vaporizable matter from fragmentary solid material comprising an annular retort having its 75 inner and outer annular walls mounted to provide for independent rotation of said walls on longitudinal axes which at least substantially approach to the horizontal, and having its outer annular wall in the shape 80 of a truncated cone, means for rotating the said inner and outer annular walls of the retort, means for maintaining said inner and outer annular walls in a suitably heated condition, means for causing said material to 85 enter one end of the retort and to travel longitudinally through the annular retort and out of the other end thereof, means for conducting away from the retort the vapors generated therein, circumferentially equidistant longitudinally extending plates within 90 the retort carried by and projecting from the inner annular wall thereof and having their free edges parallel to and normally radially spaced from the outer truncated 95 wall of the retort, other circumferentially equidistant longitudinally extending plates carried by and projecting from the truncated outer wall of the retort having their free edges parallel thereto and normally rotatively clearing the free edges of the said plates carried by the inner annular wall of the retort, and means for sliding the inner annular wall of the retort longitudinally 100 towards the smaller end of the truncated wall thereof to bring the free edges of the plates carried by the said inner wall into contact with the inner surface of the said truncated wall whereupon by relative rotative movement of the inner and outer walls 105 of the annular retort these plates will scrape away accumulated material which has adhered to the outer truncated wall of the retort.

10. An apparatus for extracting vaporizable matter from fragmentary solid material comprising an annular retort, the two walls of which are independently rotatable, means for heating the retort, means at one end for supplying the material to be treated and means at the other end for collecting the evolved vapors.

11. An apparatus for extracting vaporizable matter from fragmentary solid material comprising an annular retort, the two walls of which are independently rotatable, agitating fins on the inner face of one of the walls of the retort, means for heating the

retort, means at one end for supplying the material to be treated and means at the other end for collecting the evolved vapors.

12. An apparatus for extracting vaporizable matter from fragmentary solid material comprising an annular retort, both walls of which are jacketed and contain molten metal, means for applying heat to both the inner and outer jacketed walls for maintaining the molten metal therein in a suitable heated condition and thereby heat the

annular retort chamber, the two walls of the retort being independently rotatable and each carrying fins on its inner face for agitating the material in the retort chamber, hopper mechanism at one end of the retort, and vapor-collecting means at the other end of the retort. 15

In witness whereof, I hereunto subscribe my signature.

KENNETH EDGAR CLAYTON-KENNEDY.
